UNITED STATES PATENT OFFICE.

JAMES SHANNON, OF CANONBURY, AND WILLIAM MORRISON SIMPSON, OF HASTINGS,
ENGLAND.

OIL COOKING-STOVE.

1,382,128.

Specification of Letters Patent. Patented June 21, 1921.

Application filed November 9, 1920. Serial No. 422,938.

To all whom it may concern:

Be it known that we, JAMES SHANNON and WILLIAM MORRISON SIMPSON, subjects of the King of Great Britain and Ireland, residing at 37 Marquess road, Canonbury, in the administrative county of London, England, engineer, and 15 Godwin road, Hastings, in the county of Sussex, England, engineer, respectively, have invented certain new and useful Improvements in Oil Cooking-Stoves, of which the following is a specification.

This invention relates to cooking stoves or ranges in which oil burners of the Bunsen or atmospheric type are used, of the type having a plurality of heating burners which are supplied with the mixture of vapor and air hereinafter called the gas from a common generator co-acting with one of the burners, and has for its object primarily to provide a convenient mode of sub-division of the source of heat to a number of units so that they may be used either separately or collectively, and to provide improved means of regulating the supply of gas to said units and generally to improve this type of stove.

We attain this end by providing a chamber under the burner co-acting with the vaporizer, by leading the supply pipe for the supplementary burners out of said chamber, by the provision of means for distributing part of the gas generated by the burner co-acting with the vaporizer to the other burner or burners, by the provision of means for bringing any of the supplementary burners into or out of action, and by the provision of means for regulating the supply of gas to the burner co-acting with the vaporizer without interfering with the supply of the other burners.

In the accompanying drawings which illustrate this invention:—

Figure 1 is a view in front elevation of a stove constructed according to the present invention,

Fig. 2 is a view in plan thereof,

Fig. 3 is a view in transverse section through the main burner showing a convenient form of control,

Fig. 4 is a view in plan thereof,

Fig. 5 is a broken view in section on line $\alpha-\alpha$ Fig. 4, and Fig. 6 is a view in plan—partly in section—of the vaporizer.

Throughout the views similar parts are marked with like letters of reference.

The main burner comprises a fuel nozzle a an air induction tube b hereinafter called the mixing tube, a chamber c into which said tube leads, a burner rose or head d and a vaporizer e said vaporizer being connected to an oil container or reservoir f fitted with an air pump g and the usual fittings. In order to steady the inflow of oil and the generation of vapor a wick h may be inserted in one or both of the connecting tubes e' of the vaporizer. This wick may be formed either by winding a strand of asbestos twine on a length of wire, as shown in one of said tubes in Fig. 6 or it may consist of a plain coil of wire as shown in the other of said tubes in the same figure. The fuel jet or nozzle a which is carried by a block a' is fitted with the usual screw down valve for closing said jet or nozzle and a needle a^2 carried by said valve for cleaning said jet or nozzle.

Suitable means such as a trough l to hold methylated spirit is provided for the initial heating of the vaporizer and a similar trough m may be provided to heat up the block a' carrying the fuel jet or nozzle. These troughs may be provided with wick formed as before described or by winding asbestos twine transversely on a thin metal strip.

From the chamber c a tube n extends horizontally at right angles to the mixing tube b and serves to convey, through branch pipes n' , gas to the supplementary burners r , r , etc., said branch pipe being fitted with valves or cocks s or any other suitable form of regulating device for the purpose of controlling the supply of gas to each of the supplementary burners independent of the other or others and independently of the main burner.

To enable the main burner to be regulated without influencing the supplementary burners any suitable regulating device may be employed. A suitable one consists of a tube t adapted to slide in the tube b said tube being provided with means such as the handle t' for operating it. The tube t projects into the chamber c and lies across the orifice of the conveying tube n which is suitably shaped to engage with it, and its inner end engages with a cone-shaped projection v

mounted on the wall of the chamber. In the tube t is a slot t^2 which is of such a shape and size that in all positions which said tube may occupy it is in communication with the 5 conveying tube n , and thus at all times keeps the communication between the tube n and the generator open. The amount of gas passing to the main burner is regulated by opening and closing the inner end of the 10 tube t by varying its position in relation to the projection v . A small permanent opening between the tube t and the chamber a such as the small hole t^3 in said tube is provided so as to keep the main burner in action 15 at all times for the purpose of keeping the vaporizer hot.

The burners are mounted in a suitable and appropriate frame w for carrying cooking utensils or ovens or the like.

20 The gas may also be utilized for lighting purposes in conjunction with incandescent burners such a combination being shown by way of example in Fig. 1 of the accompanying drawing for the purpose of lighting the 25 stove. In the arrangement shown the incandescent burner y is connected with the conveying pipe n by means of a pipe such as y' .

What we claim is:—

30 1. An oil cooking stove comprising a main burner, a plurality of supplementary burners, an oil reservoir, means for creating pressure in said reservoir, a vaporizer connected to said reservoir, a chamber located below 35 and in communication with said main burner, an adjustable fuel nozzle connected to said vaporizer, an induction or mixing tube co-acting with said fuel nozzle and in communication with said chamber, a supply 40 pipe for the supplementary burners leading out of said chamber, means for controlling the supply of gas to each of said burners independently of the others and means independent of the fuel nozzle for varying the 45 amount of gas passing to the main burner head independently of the amount of gas passing to the supply pipe of the supplementary burners.

50 2. An oil cooking stove comprising a main burner, a plurality of supplementary burners, an oil reservoir, means for creating pressure in said reservoir, a vaporizer connected to said reservoir and located above and co-acting with said main burner, means for preliminary heating said vaporizer, an adjustable chamber located below the main burner, a fuel nozzle in communication with said vaporizer, an induction or mixing tube co-acting with said fuel nozzle and projecting 55 into said chamber, a supply pipe for the supplementary burners in direct communication with the induction or mixing tube, means for controlling the supply of gas from said supply pipe to each of said supplemental burn-

ers, and of valve means for putting the induction or mixing tube into communication with said chamber.

3. In an oil cooking stove the combination of an oil reservoir means for creating pressure in said reservoir, a main burner head, 70 a chamber under and in communication with said head, a vaporizer located above said head, and in communication with the oil reservoir, a fuel jet or nozzle in communication with said vaporizer, an adjustable needle valve controlling the orifice of said nozzle, an induction or mixing tube co-acting with 75 said nozzle and leading into said chamber a plurality of supplementary burner heads, a conveying tube connecting said chamber with 80 said supplementary burners, cocks or valves for regulating the gas passing to said supplementary burners, and means for regulating the relative amount of gas passing to the main and to the supplementary burners comprising a tube mounted to slide in the induction or mixing tube the inner end of 85 which projects into the chamber beneath the main burner, a coned plug mounted in said chamber and co-acting with the open end of 90 said sliding tube to form a valve, and a slot or opening in said sliding tube co-acting with the orifice of the conveying tube leading to the supplementary burners to keep said conveying tube always open to the induction or 95 mixing tube.

4. In an oil cooking stove the combination of a main burner head, a chamber under and in communication with said head, an oil reservoir, means for creating pressure in said 100 reservoir, a vaporizer located above said head and in communication with the oil reservoir, a fuel nozzle in communication with said vaporizer, an adjustable needle valve controlling the orifice of said nozzle, an induction or mixing tube co-acting with 105 said nozzle and leading into said chamber, a plurality of supplementary burner heads, a conveying tube connecting said chamber with 110 said supplementary burners, cocks or valves for regulating the gas passing to said supplementary burners, a tube mounted to slide in the induction or mixing tube the inner end of which projects into the chamber beneath the main burner, a coned plug mounted in said chamber and co-acting with the open end of 115 said sliding tube to form a valve, a slot or opening in said sliding tube co-acting with the orifice of the conveying tube of the supplementary burners to keep said conveying tube always open to the induction or 120 mixing tube and a by-pass port in said sliding tube for keeping the chamber beneath the main burner constantly open to the induction or mixing tube.

JAMES SHANNON.
WILLIAM MORRISON SIMPSON.
